UNITED STATES PATENT OFFICE.

ROBERT C. DOUGLASS, OF CHICAGO, ILLINOIS, ASSIGNOR TO ALFRED B. MCCHESNEY, OF SAME PLACE.

RAILROAD-GATE.

SPECIFICATION forming part of Letters Patent No. 499,878, dated June 20, 1893.

Application filed May 21, 1891. Serial No. 393,522. (No model.)

To all whom it may concern:

Be it known that I, ROBERT C. DOUGLASS, a subject of the Queen of Great Britain, residing at Chicago, Cook county, Illinois, have invented certain new and useful Improvements in Railroad-Gates, of which the following is a specification.

As is well known railway gates are used at crossings to prevent teams and persons crossing the railroad track. They are provided with arms intended to stretch all or part way across the roadway, called roadway arms, and also with arms extending across the sidewalk, called sidewalk arms. These arms are generally so connected that the raising or lowering of the roadway arm raises or lowers the sidewalk arm; and the object of my invention is to simplify the connection between these arms; and the invention consists in the features and details of construction hereinafter described and claimed.

In the drawings, Figure 1 is a vertical elevation of one of the gate posts with its side removed; and Fig. 2 a plan view with the top 25 of the post removed.

The post A is made in the ordinary manner, and of suitable dimensions to receive the operating parts. Within this post is journaled a shaft B, to which is secured the roadway arm C, this arm being bifurcated as shown and straddling the post in the well known manner.

Rigidly attached to the shaft B is a sector D, to which are fastened ropes or chains E, which pass over suitable pulleys and beneath the roadway, being fastened at their other ends to a similar sector in another post; it being understood that there are generally four of these posts at every crossing. A cylinder F is then constructed and supported within the post in any desired manner. Within this cylinder is placed a piston, the rod of which is connected to the sector in any desired manner. These parts are all more or less well known; and since their construction will be obvious from an inspection of the drawings, they require and will receive no further description. The sidewalk arm G is also bifurcated and is mounted upon a shaft g, which, 50 in the present construction, is shown as bent to afford room for the passage of the sector,

although this is not essential. Integral with this shaft, or separate therefrom and attached thereto, as desired, is the crank H. I then construct the link which connects the sector 55 with this crank. This link is preferably made in two parts, I and I', united by a union or screw-threaded joint J. The part I' is attached to a suitable stud or pin upon the sector, and the part I to the crank H.

The device operates as follows: In the drawings both arms are shown as brought down across the roadway and sidewalk. If it is desired to raise them, power is applied by means of the cylinder, piston and rod, to 65 rock the sector toward the left (Fig. 1) raising the arm C. As the sector rocks toward the left, the pin to which the link is attached moves downward, thereby exerting a pull upon the crank, and rocking it toward the 70 right to revolve the shaft g and raise the sidewalk arm. When the sector moves back again, this sidewalk arm is lowered by the same connections. By means of this construction I provide a simple and efficient 75 means for causing the movement of the roadway arm to move the sidewalk arm, thereby dispensing with the gear wheels and more or less complicated and expensive devices heretofore in use for this purpose.

As has already been stated, the link connecting the crank with the sector is preferably made in two parts, screw-threaded and united by a nut or union J, whereby the length of this link may be increased or diminished. 85 The object of this method of construction is to provide means for properly adjusting the gates.

As formerly constructed, it was frequently found when a gate was put up and the roadway arm raised to a vertical position, that owing to imperfect castings or other causes, the parts would be so adjusted that the sidewalk arm would only be raised one half or three-fourths of the way toward a vertical position. This difficulty can be overcome by the use of this adjustable connection; since if the sidewalk arm does not rise sufficiently high, the link can be shortened, which will pull the crank and the arm toward the right 90 (Fig. 1), while on the other hand if the arm G rises too far, the length of the link may be 95 100

increased, allowing the arm to move to its proper position. In this way the parts can be simply and securely adjusted for proper operation without the necessity of taking any 5 of them back to the shop to be altered; all possible inaccuracies being provided for by the adjustable connection.

While I have shown more or less specific forms, I do not intend to limit myself thereto, 10 since I contemplate the substitution of the equivalents; and any other suitable form of link connection may be used in place of the two part link and union joint; the gist of my invention consisting in providing a link connection, preferably adjustable, between the 15 shaft of the sidewalk arm and the operating sector.

I claim—

1. In a railway gate, the combination of an 20 operating sector, a sidewalk arm mounted on a suitable shaft, a crank on such shaft, and an adjustable link connecting the crank and sector, whereby the movement of the sector raises and lowers the sidewalk arm, substantially as described.

2. In a railway gate, the combination of a 25 gate post, a shaft journaled therein, a sector fixed to such shaft, means for revolving the

sector and shaft, a sidewalk arm mounted on a shaft journaled in such post, a crank on 30 such shaft, and an adjustable link connecting the crank and sector, substantially as described.

3. In a railway gate, the combination of an 35 operating sector, a sidewalk arm supported by a suitably journaled shaft, such shaft having a crank, and a link connecting such crank and the sector, one member of the link being secured to the sector and one to the crank, the two members being connected by a suitable joint, whereby the length of the link may be varied to adjust the relative position of the parts of the gate, substantially as described.

4. In a railway gate, the combination of a 40 45 gate post, an operating sector mounted on a shaft journaled in said post, a sidewalk arm mounted on a shaft journaled in such post, such shaft being bent to pass around the edge of the sector and carrying a crank, and an adjustable link connecting the sector and the 50 crank, substantially as described.

ROBERT C. DOUGLASS.
